UNITED STATES PATENT OFFICE.

MAX PERES, OF SOLINGEN, GERMANY.

DESIGN FOR A POCKET-KNIFE.

46,414.

Specification for Design.

Patented Sept. 15, 1914.

Application filed July 23, 1913. Serial No. 780,798. Term of patent 3½ years.

To all whom it may concern:

Be it known that I, MAX PERES, a subject of the German Emperor, and resident of Solingen, Germany, have invented a new, original, and ornamental Design for Pocket-Knives, of which the following is a specification, reference being had to the accompanying drawing, forming part thereof.

Figure 1 is a plan view of a knife, showing my new design, while Fig. 2 is an underside plan view of the same.

I claim:

The ornamental design for a pocket-knife, as shown.

MAX PERES. [L. S.]
